DESIGN FOR A BUCKLE

Paul W. White and William R. Kent, Fort Lauderdale, Fla., assignors to Parva Products Company, Chicago, Ill., a corporation of Delaware

Application September 9, 1943, Serial No. 111,083

Term of patent 7 years

To all whom it may concern:

Be it known that we, Paul W. White and William R. Kent, citizens of the United States, residing at Fort Lauderdale, in the county of Broward and State of Florida, have invented a new, original, and ornamental Design for a Buckle, of which the following is a specification, reference being had to the accompanying drawing, forming a part thereof.

In the drawing:

Fig. 1 is a perspective view of a buckle embodying our new design;

Fig. 2 is a top plan view of the buckle shown in Fig. 1;

Fig. 3 is a side elevational view of the buckle shown in Fig. 1; and

Fig. 4 is a front end view of the buckle.

The characterizing features of our new design reside in the configuration of the buckle frame as shown in full lines.

We claim:

The ornamental design for a buckle, substantially as shown and described.

PAUL W. WHITE.
WILLIAM R. KENT.
